By Percy H. Moore
A.T.T.Y.

UNITED STATES PATENT OFFICE.

HERMAN CASLER, OF CANASTOTA, NEW YORK, ASSIGNOR TO SHERWOOD BROS. MFG. CO. INC., OF CANASTOTA, NEW YORK.

WAGON.

Application filed February 11, 1924. Serial No. 692,110.

To all whom it may concern:

Be it known that HERMAN CASLER, a citizen of the United States of America, residing at Canastota, in the county of Madison and State of New York, has invented certain new and useful Improvements in Wagons, of which the following is a specification.

My invention relates to wagons and more particularly to the so called child's coaster wagon or cart.

The principal object of my invention is to provide a simple, economical and efficient running gear.

Other and further objects and advantages of the invention will be in part obvious and in part described as the specification is proceeded with.

In the accompanying drawings forming part of this specification:

20 Figure 1 is a side elevation of a child's wagon showing the invention, one of the front wheels of the wagon being removed;

Figure 2 is a bottom plan view thereof with all wheels removed;

25 Figure 3 is a section on the line 3—3 of Figure 1 partly broken away; and

Figure 4 is a detail of the members or brackets for supporting the rear end of the wagon.

30 Referring more particularly to the drawings, 5 denotes the body of the cart, 6 and 7 the front and rear axles, and 8 and 9 the respective front and rear wheels therefor. The body 5, is supported at its front and rear ends upon the respective axles by means about to be described.

35 Mounted on the front axle is a horizontally disposed substantially V shaped frame member 10, comprising a transverse bar or strap 11, right angular forwardly projecting parallel portions 12 and forwardly inclined tongue straps 13. A U shaped spacing member 14 is secured between the extremities of the tongue straps by means of bolts 15 and

40 16. A brace 17, is looped around the bolt 15 and extends upwardly and rearwardly to the wagon body 5, where it is secured by means of a cotter pin 18, passing through a king bolt 19, hereinafter referred to more specifically.

45 A horizontally disposed bearing plate 20, rests upon and is connected to the transverse

bar or strap 11 of the member 10 by bolts or rivets 21, passing through a flange 22, depending from the rear edge of the plate 20, which plate is also provided with oppositely disposed depending notched legs 23, adapted to engage over the front axle 6.

50 Secured to the bottom of the wagon body 5, by means of bolts 24, is a downwardly bowed bolster 25, which rests upon and is supported by the bearing plate 20. A brace 26, secured to the center of the wagon body by bolt 27, at its upper end, extends at its lower end between the bolster 25 and the bearing plate, the bolster being formed with a recess 28, to snugly receive the brace. The king bolt 19, extends through the upper end of brace 17, thence through the bolster 25, the lower end of brace 26 and thence through the bearing plate 20, a cotter pin 29 being employed at the lower extremity of the king bolt for an obvious purpose. It will be understood that the member 10, axle 6, bearing plate 20 and brace 17, are free to turn about the king bolt as an axis, when the front wheels are turned by means of the tongue or handle 30.

55 The rear portion of the wagon body is supported upon the rear axle 7, by means of legs 31, depending from opposite sides of the body 5, and secured thereto by bolts 32. The lower portions of the legs 31 are curved upwardly and rearwardly to form a pocket or recess 32, in which the axle is partially seated, and the lower extremity of each leg is formed with an upwardly curved reduced extension 33. Straps 34, one for each leg 31, are secured to the wagon body by bolts 35, and extend downwardly and rearwardly therefrom, the upwardly curved ends of these straps extending beneath and partially around the rear axle adjacent the points of engagement between the rear axle and the legs 31. These straps 34, are apertured as 36 to receive the reduced extensions 33, previously referred to.

60 In assembling the parts, the extension 33 is inserted in the position illustrated in Figure 4 of the drawing, before the upper end of the straps 34 are secured to the wagon body by bolts 35. When these bolts are tightened up, it will be seen that the extremity of the straps 34, will rest upon the

reduced extensions 33, and the curved portions of the straps 34 will be pulled up tightly against the lower periphery of the axles, thus effecting a very snug connection 5 between the various parts.

Having thus described my invention:

What I claim is:

1. A wagon comprising an axle, a substantially V-shaped frame member pierced 10 by and supported upon said axle, a bearing plate secured to said frame member and having notched legs engaging said axle, a bolster connected to the wagon body and resting upon said bearing plate, a front 15 brace extending from the wagon body to the frame member, and a second brace extending from the wagon body to a point between the bearing plate and the bolster and a king bolt connected to the wagon body and passing through the upper end of the first mentioned brace through the bolster and thence 20 through the lower end of the second brace and through the bearing plate.

2. A wagon comprising an axle, a frame 25 member supported by said axle, a bearing plate having notched legs and a depending flange, the notched legs engaging over the axle and the flange being secured to the frame member, a bolster secured to the 30 wagon body and resting upon said bearing plate, and means for pivotally connecting the bearing plate to the bolster.

3. A wagon comprising an axle, legs secured to and depending from the wagon 35 body and provided with axle engaging portions, straps secured to the body portion adapted to extend beneath the axle, and means on the axle engaging portions of said legs cooperating with means on said straps

for securing said legs and straps in rigid 40 interlocking engagement with each other.

4. A wagon comprising an axle, legs secured to and depending from the wagon body and provided with curved end portions adapted to seat upon and partially receive the axle, straps secured to the wagon body provided with curved apertured ends 45 extending beneath and partially around the axle, the end portions of the said legs having reduced extensions passing through the 50 said apertures and locking said legs and straps to said axle.

5. A wagon comprising an axle, legs secured to and depending from the wagon body and provided with axle engaging portions, straps secured to the body portion, and means on the axle engaging portions of 55 said legs cooperating with means on said straps for rigidly clamping said legs and said straps to said axle.

6. A wagon comprising an axle, a frame member supported by said axle, said frame member comprising a transverse bar, a bearing plate having notched legs and a depending flange, the notched legs engaging over 65 the axle and the flange engaging behind and being secured to the transverse bar of said frame member, a bolster secured to the wagon body and resting upon said bearing plate, and means pivotally connecting the 70 bearing plate to the bolster.

In testimony whereof I affix my signature in presence of two witnesses.

HERMAN CASLER.

Witnesses:

E. B. JACOB,
M. M. HESLIN.
